(No Model.)

J. G. BRYAN.

VALVE FOR WATER CLOSET RESERVOIRS.

No. 341,372.

Patented May 4, 1886.

UNITED STATES PATENT OFFICE

JAMES G. BRYAN, OF LAVALLETTTE, NEW JERSEY.

VALVE FOR WATER-CLOSET RESERVOIRS.

SPECIFICATION forming part of Letters Patent No. 341,372, dated May 4, 1886.

Application filed March 15, 1886. Serial No. 195,200. (No model.)

To all whom it may concern:

Be it known that I, JAMES G. BRYAN, a citizen of the United States, residing in Lavallette, Ocean county, New Jersey, have invented certain Improvements in Valves for Water-Closet Reservoirs, of which the following is a specification.

One object of my invention is to so construct a valve for water-closet reservoirs that the proper operation of the valve will be insured when the level of water in the reservoir is low; and a further object is to prevent the roaring noise due to the rush of air into the overflow-tube of the valve.

15 In the accompanying drawings, Figure 1 is a sectional view of the valve and sufficient of the reservoir to illustrate my invention, the valve being closed; Fig. 2, a similar view showing the valve open; Fig. 3, a sectional plan on the line 1 2, Fig. 2; Fig. 4, a sectional plan on the line 3 4, Fig. 2; and Fig. 5, a view showing the air-cut-off valve in a different position from that shown in Figs. 1 and 2.

25 A represents part of the casing of the water-reservoir, to which is secured the discharge-tube B, a flange, a, on which bears upon the lead lining of the reservoir, while a retaining-nut, a', bears upon the under side of the shell or casing of the reservoir. To the flange a is 30 screwed the lower section, b, of the valve-casing D, the upper end of said section b being screwed into a ring, d, which also receives the lower end of the upper section, b', of the casing, a partition, e, being confined between the 35 two sections, as shown in Figs. 1 and 2.

F is a valve, which is adapted to a raised annular seat formed on the upper end of the discharge-tube B, this valve having a tubular stem, G, which passes through a stuffing-box, g, 40 on the partition e, and has a piston, h, fitting snugly to the upper portion, b', of the valve-casing, and provided with a suitable packing, so as to prevent leakage. In this piston is an opening, i, to which is adapted a pivoted valve, k, by the adjustment of which the area afforded 45 by the opening i for the exit of water may be increased or diminished, and in the partition e is an opening, m, to which is adapted a flap-valve, n, opening upward.

50 When the valve-stem G is lifted so as to raise the valve F from its seat, as shown in Fig. 2,

water can flow freely from the reservoir through ports p in the lower portion of the valve-casing D, and can pass from the reservoir through the discharge-tube B. As the valve is lifted, 55 water is drawn through the opening m in the partition e into the chamber of the valve-casing above said partition, and when the valve-stem is released and said valve-stem is depressed, owing to the action of a weight, s, 60 supported thereon, the descent of the valve is retarded to an extent dependent upon the adjustment of the valve k on the piston h, for as the valve n prevents any escape of water downward through the opening n in the partition e all of the water trapped between said partition and the piston h of the valve-stem must escape through the contracted passage afforded by the partially-obstructed opening i, 65 so that the time occupied by the valve in its descent, and the extent of flushing of the water-closet can be regulated to a nicety by the adjustment of the valve k.

As the supply of water for regulating the descent of the valve is drawn from the lower 75 portion of the valve-casing, the apparatus will work properly, even when the level of water in the reservoir is low, thus overcoming an objection to that class of valves in which the supply of water for regulating the descent of 80 the valve is received from the top of the valve-casing as the valve is lifted.

To the upper end of the tubular stem G of the valve is secured a cap, J, in which are a series of ports, w, closed, under ordinary circumstances, by a ring, x, carried by an annular float, y. Access of air to the tubular stem G of the valve is thereby cut off, and the roaring noise due to such inlet of air is effectively prevented. As the water rises in the 90 reservoir, however, to the overflow-point, the valve x is lifted by the float y, so as to open the ports w and permit the surplus water to escape through the hollow stem of the valve, as usual.

95 I claim as my invention—

1. The combination of the valve-casing having two chambers separated by a partition, a valve-stem having a valve in the lower chamber of the casing and a piston in the upper chamber of the same, a valved opening in the partition between the two chambers, and an

opening in the piston provided with a regulating-valve, all substantially as specified.

2. The combination of the hollow valve-stem having a ported cap, with a closing-valve consisting of a sleeve adapted to slide on said ported cap, and a float connected to said sleeve, all substantially as specified.

In testimony whereof I have signed my name to this specification in the presence of two subscribing witnesses.

JAMES G. BRYAN.
